UNITED STATES PATENT OFFICE.

FRANK D. KIMBER, OF CORNING, NEW YORK, ASSIGNOR OF ONE-HALF TO
ISAIAH JOHNSTON, OF SAME PLACE.

LAMP-BURNER.

SPECIFICATION forming part of Letters Patent No. 367,817, dated August 9, 1887.

Application filed February 15, 1887. Serial No. 227,655. (No model.)

To all whom it may concern:

Be it known that I, FRANK D. KIMBER, a citizen of the United States, and a resident of Corning, in the county of Steuben and State 5 of New York, have invented certain new and useful Improvements in Lamp-Burners, of which the following is a specification.

My invention relates especially to devices for holding the chimney upon a lamp-burner; 10 and it consists in the novel construction and arrangement of parts hereinafter more particularly described.

In the accompanying drawings, Figure 1 represents a side view of a lamp-burner embodying my invention. Fig. 2 represents a 15 similar view thereof at a right angle to Fig. 1. Fig. 3 represents a plan or top view thereof.

Similar letters of reference indicate corresponding parts.

20 The letter A indicates the rim or chimney-gallery, B the screw-neck, and C the cone of the burner, these parts being arranged in substantially the usual manner.

D E are the chimney-holding arms, which 25 are located diametrically opposite to each other upon the chimney-gallery A, one (D) being fixed to said gallery, and the other (E) being adjustable thereon in horizontal direction. Both the arms D E are shaped to 30 form to the lower part of the chimney that may be used upon the burner, and in the example shown they have straight upright shanks and outwardly-bent ends or extremities to engage with a globular chimney from an inward direction—that is to say, when the adjustable arm E is set to a position corresponding with the fixed arm, as shown in Fig. 1. The adjustable arm E has its bearings in the chimney-gallery A, together with yoke G, properly 35 secured thereto, it resting upon the gallery or upon the yoke, by means of a collar, i, and to facilitate the adjustment of said arm it is provided at the lower end with a handle, J, be-

neath the gallery and which may be in one piece with the arm, the whole being of wire. 45

For the purpose of locking the adjustable arm E in a normal position, the chimney-gallery A is provided with a notch, o, (see Fig. 2,) which is at one end of a downwardly-inclined edge, n, on said gallery, so that when the 50 handle J is swung in the direction of the notch it rides over said inclined edge and springs into the notch, thereby preserving a fixed position, it being only necessary to withdraw the handle from the notch in order to permit the 55 adjustable arm to be set for disengaging the chimney. The locking-notch o should be in proper relative position to the shape of the adjustable arm E; and in order to limit the rearward motion of the handle J the chimney-gallery may be provided with a stop, s, to arrest the handle. 60

It is evident that the arms D E may be arranged to engage the lamp-chimney from an outward direction and may be of any suitable 65 shape to effect the desired purpose.

What I claim as new, and desire to secure by Letters Patent, is—

In a lamp-burner, the combination of a pair of arms, one fixed and the other adjustable horizontally and provided with a handle on its lower end, and both shaped to engage the interior of the lamp-chimney, a chimney-gallery having an inclined edge provided with a notch to receive said handle for locking the adjustable arm in normal position, a yoke, G, carrying the arm E, and a collar, i, on said arm, all substantially as and for the purpose herein shown and described. 75

Signed at Corning, in the county of Steuben 80 and State of New York, this 22d day of December, A. D. 1886.

FRANK D. KIMBER.
